UNITED STATES PATENT OFFICE.

WILLIAM HERBERT SHIELDS, OF COTTESLOE, WESTERN AUSTRALIA, AUSTRALIA.

ARCHED CONSTRUCTION OF WEIRS AND OTHER RETAINING-WALLS.

No. 927,290.

Specification of Letters Patent.

Patented July 6, 1909.

Application filed April 13, 1907. Serial No. 368,063.

To all whom it may concern:

Be it known that I, WILLIAM HERBERT SHIELDS, a subject of the King of Great Britain, residing at Cottesloe, in the State of 5 Western Australia and Commonwealth of Australia, have invented certain new and useful Improvements in Arched Construction of Weirs and other Retaining-Walls, of which the following is a specification.

10 The purpose of this invention is to construct weirs, embankments, retaining walls and analogous constructions in a multiple arched manner whereby the strength of the material is brought into operation and taken 15 advantage of instead of by the dead weight alone as is the case now in a solid construction of the usual wedge shape section.

The invention is applicable in its use for all classes of weirs and retaining walls 20 whether of brick, concrete and stone or masonry and similar constructive work and the invention essentially consists in the employment of a series or multiple of arches whereby the span is divided or broken up into any 25 number of arches and abutments. This design of construction results in economy of material and in the maximum effective strength being obtained from the body of material which may be employed.

30 In my invention as applied to a weir the span or cross section of the valley is divided up by a series of piers or abutments, the latter being connected to each other by arches. The face of the weir when constructed according to this invention slopes at an approved angle and the weir is of a hollowed out or arched section instead of being of the solid wedge shape.

In order that the construction of the invention may be clearly understood reference 40 will be made to the attached drawings in which:

Figure 1 is a perspective view showing my invention as applied to a dam or weir. Fig. 45 2 is a front face elevation of same. Fig. 3 being a top plan view and, Fig. 4 a sectional elevation of the construction shown in Fig. 2.

In these drawings the weir or retaining wall is built across the face of the valley a' , 50 said weir being composed or made up by a series or multiple of arches as b and supported by the walls or abutments c . The arches

as b constituting the weir may be made larger at the foot as d and tapering to the crown as e and as clearly shown in Fig. 4. 55 Between each of the abutments c is formed the resultant recesses f which give the hollowed out formation to their weir. The reservoir is denoted by the letter g while h is the bridge or parapet across the weir. 60

In order to reinforce the wall to prevent its shifting under the weight of the water or other material it retains, and also to provide a liquid seal to prevent escape of the liquid, I provide a depending rib x which extends 65 throughout the length of the lower edge of the slanting wall formed by the row of arches b , this rib being formed by packing the cement or laying the brick or other material into a correspondingly arranged trench. 70 The upper rear edge of the wall formed by the series of arches b is also provided preferably with a series of longitudinally spaced elevated piers y on which is mounted the parapet or bridge h .

75 What I do claim and desire to obtain by Letters Patent is:—

1. A structure of the class described comprising a series of suitably spaced vertical walls having their forward edges inclined, a 80 series of arches spanning the spaces between said walls and lying substantially in the plane of the inclined edges thereof, the lower edges of said arches merging into a rib continuous with the lower edges of the arches 85 and arranged in the plane of the lower edges of said walls, said rib being adapted to engage in a longitudinal trench.

2. A structure of the character described, 90 embodying a set of suitably spaced supporting walls, a series of arches spanning the spaces between the walls and arranged in inclined relation thereto, a series of longitudinally spaced piers supported above the upper edges of the several arches and elevated 95 above the latter, and a parapet mounted on the piers.

In testimony whereof I have hereunto set my hand in presence of two subscribing witnesses.

WILLIAM HERBERT SHIELDS.

Witnesses:

RICHARD SPARROW,
ROSS EAST.
